United States Patent Office

Des. 185,344
Patented June 2, 1959

185,344

CANDY CONFECTION

Lawrence S. Bortz, Jr., Shillington, Pa.

Application February 25, 1959, Serial No. 54,732

Term of patent 14 years

(Cl. D82—2)

FIG. 1.

FIG. 2.

FIG. 3.

Fig. 2 is a bottom view thereof; and

Fig. 3 is a side elevational view thereof.

I claim:

The ornamental design for a candy confection, substantially as shown.
